UNITED STATES PATENT OFFICE

DAVID C. GARROWAY, OF BELMONT, AND CHESTER D. AINSWORTH, OF WOLLASTON, MASSACHUSETTS, ASSIGNORS TO CONDIT ELECTRICAL MANUFACTURING CORPORATION, OF SOUTH BOSTON, MASSACHUSETTS, A CORPORATION OF MASSACHUSETTS

ELECTRIC SWITCH AND CONTACT STRUCTURE THEREFOR

Application filed January 2, 1926. Serial No. 78,818.

This invention relates to electric switches and has for an object improvements in the construction of contact members therefor.

A common type of contact member comprises a tube into which the cooperating contact member, usually a rod, is moved to complete the circuit. The tube is split along its length to form a plurality of separate segments or shoes, and a coiled annular spring encircles the segments to press them yieldingly against the rod.

When the switch is opened under heavy load it sometimes happens that the circuit-interrupting arc enters the space between two adjacent segments and burns and severs the spring, so that good pressure contact cannot be made when the switch is again closed.

It is an object of this invention to provide a segmental contact member of the type above set forth with spring-means to urge the segments against the cooperating contact rod, the spring-means being so arranged that the circuit-interrupting arc cannot readily gain access thereto.

A further object is the provision of a split contact member so arranged that each segment thereof is independently positively connected electrically in the circuit through the switch.

A further object of the invention is the provision of a bell-type contact member and supporting means therefor so arranged that the contact member is self-centering on the cooperating contact rod, thereby to facilitate engagement between the two regardless of small departures from absolute alignment.

A further object is generally to improve the construction and operation of electric switches and circuit interrupters.

Certain features of this invention are disclosed in a co-pending application of David C. Garroway, filed January 2, 1926, Serial No. 78,819.

Fig. 1 is a more or less diagrammatic representation of the separable contact member of an electric switch in which this invention is incorporated.

Fig. 2 is a side elevation, partly in section, of the stationary contact structure of Fig. 1, in which the invention is embodied.

Fig. 3 is a plan view of the contact structure of Fig. 2, the supporting bracket being broken away.

Fig. 4 is a section along line 4—4 of Fig. 2.

Fig. 5 is a side elevation of one of the segments of the bell contact member. 55

As shown in Fig. 1 the electric switch embodying the invention includes the stationary switch members 10 and the movable switch member 12. The movable switch member includes a cylindrical contact rod 14 which is extended vertically upward from a supporting bar 16 and is adapted to enter a stationarily-supported tubular contact member or bell 18 carried by a stationary switch member. 60

The contact bell includes a metal tube which has an internal vertical passage 20 extended from end to end thereof in which the contact rod 14 is adapted to be received and to make contact. The passage has an outwardly flared lower entrance 22 which facilitates entry of the contact rod into the bell and also serves to effect the lateral shifting of the bell into alignment with the rod, if the bell is initially displaced from such alignment. The upper end of said passage is also provided with an outwardly flaring end 24. 70

Said bell is supported in a bracket 26 which is fixed to and is in electrical connection with a stationary switch member 10. Said bracket is formed or provided with an approximately circular head 28 in which said bell is received. Said head is formed with a circular recess 30 in its top face and a wall 32 which closes the bottom of the recess. Said wall is formed with an aperture 34 through which the contact bell is extended. 80

A cover plate 36 is disposed on said head to cover the top of said recess and is provided with an aperture 38 through which said bell is extended. Said cover plate is secured removably in the aforesaid relation by bolts 40 which extend through said cover plate and are screw-threaded into said head. The contact bell is provided with a radially-outstanding annular flange 42 intermediate its ends, which flange is disposed within said recess 30 and is adapted to rest upon the bottom wall 32. Said recess 30 is arranged to 85

90

95

100

be substantially greater in diameter than the diameter of said flange 42 so that the bell can move freely, or float, therein whereby to be self-aligning with the movable contact member. The height of said recess, however, is arranged to be but little greater than the thickness of the flange, so that the bell will be restrained against any material amount of vertical movement.

5 Said contact bell is slit radially from end to end in a manner to form a plurality of separate segments or shoes 44, three shoes being here shown. Means including spring elements are provided to urge said shoes inwardly toward their common center and said said spring elements are arranged to be concealed and shielded against the circuit-interrupting arm. Said means includes a ring 46 which is disposed within said recess 30 and encircles the flange 42 of said contact bell. Said ring is provided with a plurality of radially inwardly directed pins 48 which have screw-threaded outer ends 50 which are screw-threaded removably into said ring.

10 Said pins are received in radially inwardly directed recesses 52 formed in the shoes 44. As here shown, each shoe is provided with two recesses in which pins are disposed. Springs 54 encircle said pins and are received 15 in enlargements 56 of said recesses and are approximately completely enclosed within said recesses. The inner ends of said springs bear against shoulders 60 of said shoes and the outer ends bear against said ring 46. The 20 arrangement is such that said springs tends constantly to urge said shoes inwardly toward the common center and thereby to firm contact with the movable contact rod 14 while the pins 48 serve to guide said shoes during such movement. The springs are 25 practically entirely enclosed within the shoes and thereby occupy positions inaccessible to the circuit-interrupting arc. The bottom wall 32 of the recess further shields said springs 30 against contact with the circuit-interrupting arc and the hot gases resulting therefrom.

Said cover plate 36 is provided with an upwardly extended wall 62 which is terminated at its upper end in an inwardly-directed flange 64 whereby to form an enclosure or 35 housing 66 about the upper position of the contact bell. Means are disposed within said enclosure by which each contact shoe 44 is independently and positively electrically connected with the bracket 26. Said means includes a plurality of flexible leads 68, two being associated with each shoe. Said leads are secured to and connected electrically with the shoes by means of screws 70. Slots 72 40 are formed in the flange 64 and upper portion of the wall 62 of the cover plate adjacent each shoe and the leads are extended in pairs outwardly through said slots. The outer ends of said pairs of leads are reflexed away 45 from each other and against the wall 62,

in which position they are secured by screws 74. This arrangement permits the bell to float within its supporting bracket, and permits independent movement of each shoe, while maintaining positive electrical connection between the shoes and the bracket. 70

We claim:

1. A contact structure for electric switches including a tubular contact member, a ring encircling said contact member, a plurality of spring elements connecting said ring and contact member, and a housing in which said contact member and ring are received loosely and can move laterally in all directions. 75

2. A contact structure for electric switches including a floating tubular contact member having a plurality of independent segments, a ring encircling said contact member and floating therewith, and resilient elements connecting said segments and ring characterized by independently urging said segments toward each other. 80

3. A contact structure for electric switches including a housing, a tubular contact member therein having a plurality of independent segments, a floating ring loosely received in said housing and encircling said contact member and adapted to move laterally in all directions, and pins carried by said ring which are received loosely in recesses in said segments. 90

4. A contact structure for electric switches including a housing, a tubular contact member having a plurality of independent segments, a floating ring disposed loosely in said housing and encircling said contact member, and pins carried by said ring which are received loosely in recesses in said segments, and springs encircling said pin and having bearings on said segments and also on said ring. 100

5. A contact structure for electric switches including a tubular contact member having a plurality of independent segments, and a floating ring encircling said contact member, resilient pressure-applying elements independently connecting said segments and ring, said segments and ring also having loosely interlocking parts characterized by preventing undue relative angular displacement between 110 said ring and segments. 115

6. A contact structure for electric switches including a housing, a tubular contact member disposed therein having a plurality of independent segments provided with recesses 124 therein, a floating ring loosely received in said housing encircling said contact member at said recesses, and compression springs contained in said recesses and having bearings against said ring. 125

7. A contact structure for electric switches including a tubular contact member having a plurality of independent segments provided with recesses therein, a ring loosely encircling said contact member closely and arranged in 13

- covering relation with said recesses, and compression springs received in said recesses and having bearings against said ring.
8. A contact structure for electric switches including a tubular contact member having a plurality of independent segments provided with recesses therein, a ring closely encircling said contact members and arranged in covering relation with said recesses, pins carried by said ring and extended into said recesses, and springs encircling said pins in said recesses and having bearings against said segments and said ring. 70
9. A contact structure for electric switches including a supporting member providing a pair of superimposed enclosures, a tubular contact member disposed loosely in both enclosures, said contact member including a plurality of relatively movable contact segments, resilient supporting means for said segments disposed in the one enclosure, and flexible leads disposed mainly in said other enclosure and having connections with said segments therein. 75
10. A contact structure for electric switches including a supporting member providing a pair of superimposed enclosures, a tubular contact member disposed loosely in both enclosures, said contact member including a plurality of relatively movable contact segments, resilient supporting means for said segments disposed in the one enclosure, and flexible leads disposed mainly in said other enclosure and having connections with said segments therein, said flexible leads extended externally of the enclosure and having means securing their extended ends externally to said supporting member. 80
11. A contact structure for electric switches including a supporting member having a recess therein, an apertured bottom wall for the recess, an apertured cover plate for the top of the recess, and a tubular contact member extended through said apertures and having an outstanding flange disposed in said recess between said cover-plate and bottom wall, said contact member being free to float within said recess. 85
12. A contact structure for electric switches including a supporting member having a recess therein, an apertured bottom wall for the recess, an apertured cover plate for the top of the recess, and a tubular contact member extended through said apertures and having an outstanding flange disposed in said recess between said cover-plate and bottom wall, said tubular contact member having a plurality of independent contact segments, a ring disposed loosely within said recess about said flange, and springs connecting said ring and segments. 90
13. A contact structure for electric switches including a supporting member having a recess therein, an apertured bottom wall for the recess, an apertured cover plate for the top of the recess, and a tubular contact member extended through said apertures and having an outstanding flange disposed in said recess between said cover-plate and bottom wall, said tubular contact member having a plurality of independent contact segments, a ring disposed loosely within said recess about said flange, and springs received in recesses in the flange section of said segments and having bearings against said ring. 95
14. A contact structure for electric switches including a supporting member having a recess therein, an apertured bottom wall for the recess, an apertured cover plate for the top of the recess, and a tubular contact member extended through said apertures and having an outstanding flange disposed in said recess between said cover-plate and bottom wall, said tubular contact member having a plurality of independent contact segments, a ring disposed loosely within said recess about said flange, pins carried by said ring and extended loosely into recesses in the flange-sections of said segments, and springs received in said recesses and having bearings against said segments and said ring. 100
15. A contact structure for electric switches comprising a plurality of associated contact shoes disposed side by side to form a tubular contact member, independent compression springs acting independently on each of said shoes, and means including a floating abutments surrounding said contact shoes and cooperating with said compression springs to transfer pressure on one shoe through said springs to other shoes. 105
16. A contact structure for electric switches comprising a plurality of cooperating and independently-movable contact shoes, independent spring-pressure applying means for each shoe, and means acting upon application of pressure on one shoe to increase the spring pressure on another shoe including a floating rigid ring surrounding said shoes and connecting said spring-pressure applying means. 110
17. An electric switch having a tubular contact member comprising a plurality of contact segments having independent resilient supports arranged to urge said segments together, a cooperating contact member comprising a rod movable into and out of said tubular contact member, a housing within which said tubular contact member is loosely disposed, whereby it is free to move laterally to align itself with said cooperating contact member, and means including an abutment for said resilient supports loosely surrounding said tubular contact segments and laterally movable therewith in the housing, whereby to maintain a constant pressure on said segments regardless of lateral displacements thereof in the housing. 115
18. A contact structure for electric switches including a housing, a tubular segmental contact member, and resilient means to support 120
19. A contact structure for electric switches including a housing, a tubular segmental contact member, and resilient means to support 125

it yieldingly including compression springs received in recesses in each segment of said contact member, and relatively fixed abutment means for the similar ends of said springs received loosely in said housing and arranged upon yielding movement of said contact segments to cooperate therewith to completely enclose said springs.

19. A contact structure for electric switches including a housing, a tubular contact member having a plurality of independent segments received loosely in said housing, means independently to urge each of said segments toward the others, and means supported loosely in said housing independently of said contact member to shield said urging means from the circuit interrupting arc.

20. A contact structure for electric switches including a housing, a multi-part contact member having independent resilient means to support the parts yieldingly, floating supporting means for said resilient means, said resilient means being disposed mainly within and enclosed by said parts.

25 In testimony whereof, we have signed our names to this specification.

DAVID C. GARROWAY.
